UNITED STATES PATENT OFFICE

131,382

DESIGN FOR A BURIAL CASKET OR SIMILAR ARTICLE

Maxwell E. Ramsey, Clayton, Mo.

Application October 15, 1941, Serial No. 103,774

Term of patent 3½ years

To all whom it may concern:

Be it known that I, Maxwell E. Ramsey, a citizen of the United States, residing at Clayton, county of St. Louis, State of Missouri, have invented a new, original, and ornamental Design for a Burial Casket or Similar Article, of which the following is a specification, reference being had to the accompanying drawing, forming part thereof, in which—

Fig. 1 is a plan view of a burial casket, showing my new design;

Fig. 2 is a side elevational view thereof; and
Fig. 3 is an enlarged front elevational view of one of the escutcheon members shown in Figs. 1 and 2.

I claim:

The ornamental design for a burial casket or similar article, as shown and described.

MAXWELL E. RAMSEY.
